UNITED STATES PATENT OFFICE.

GEORGE W. PARKS, OF BROOKLYN, NEW YORK, ASSIGNOR TO HIRAM HOWARD AND STEPHEN C. HOWARD, OF PROVIDENCE, RHODE ISLAND.

POCKET-BOX.

SPECIFICATION forming part of Letters Patent No. 396,110, dated January 15, 1889.

Application filed October 8, 1888. Serial No. 287,551. (No model.)

To all whom it may concern:

Be it known that I, GEORGE W. PARKS, of Brooklyn, Kings county, and State of New York, have invented a certain new and useful Improvement in Pocket-Boxes, of which the following is a specification.

I will describe a pocket-box embodying my invention, and then point out the novel features in a claim.

10 My improvement consists in a box having a compartment or chamber for matches, a compartment or chamber for postage-stamps formed in one side of the match-chamber by bending the material of the box, a cover for 15 the latter, and a cover for the match compartment or chamber designed, when closed, to retain the stamp-chamber cover in place.

In the accompanying drawings, Figure 1 is a side view of a box embodying my improvement with the covers closed. Fig. 2 is a similar view with both covers open. Fig. 3 is a central longitudinal section. Fig. 4 is a transverse section.

Similar letters of reference designate corresponding parts in all the figures.

A designates the body of the box.

B designates a cover hinged to the upper end of the body A at one side.

C designates a spring secured to the body 30 near the lower part and pressing at the upper end against a projection, D, affixed to the cover B.

The box as thus far described is substantially like a common form of pocket match-box. It is, however, provided with a chamber or compartment, E, in one side, which is closed at its ends. This is formed by bending a portion of that side inwardly, or by forming a hole in one side from the upper edge nearly

to the bottom, and securing a bent strip of 40 metal in rear of said hole. This inwardly-bent portion or strip forms a partition between the main chamber or compartment of the box which is intended for receiving matches, and the smaller compartment or chamber, E, which 45 is adapted for the reception of postage-stamps.

The side edges of the compartment or chamber E are provided with grooves. A sliding cover, F, is fitted in these grooves. The cover and the upper end of the back of the stamp 50 compartment or chamber are shown as provided with stops G, which preclude the entire removal of the cover F.

When the cover F is slid down to close the stamp compartment or chamber, the main 55 cover B may be swung down to close the match compartment or chamber. It will then extend across the upper edge of the cover F of the stamp compartment or chamber and retain it in position.

What I claim as my invention, and desire to 60 secure by Letters Patent, is—

A box having a compartment or chamber for matches, having an inwardly-bent portion forming a compartment or chamber for postage-stamps closed at its ends, a sliding cover for the latter, a swinging cover for the match compartment or chamber, the said swinging cover extending across the said sliding cover when the compartments or chambers are 65 closed, and stops for preventing the entire removal of the sliding cover, substantially as 70 specified.

GEORGE W. PARKS.
